SHOE PRESSING MACHINE

Maxwell C. Suerken, Erie, Pa., assignor to Lamac
Process Company, Erie, Pa., a corporation of
Delaware

Application July 9, 1936, Serial No. 89,723

9 Claims. (Cl. 12—38)

The present invention is directed to improvements in shoe pressing machines of the type illustrated in the patent to R. F. McClenathan No. 2,004,820 June 11, 1935. In operating these shoe pressing machines, the sole is secured to the bottom of the shoe with cement. In fully securing the sole to the shoe the parts of the shoe bottom and the sole are held in engagement by pressure mechanism until there is sufficient setting of the cement to definitely secure the parts together. Structures heretofore made have provided sole supports formed of resilient rubber on which the sole was pressed during the cementing operation, but such devices have not been supplied with any included means for heating the supporting surfaces so as to accelerate the setting of the cement.

In the present invention the sole support is preferably formed of resilient rubber in which the resilience of the rubber controls the cushioning effect of the support and is provided with a heating element designed to heat the cemented surfaces in a simple and convenient manner without subjecting the rubber of the support, or the sole or lighter parts of the shoe to injurious heat. In the exemplification shown the heating element is incorporated in the resilient rubber support which assures the distribution of the clamping action throughout the sole. In carrying out the present invention, the heating element is incorporated directly in the body of the rubber support. It is so related in capacity and is subjected to so light a voltage as to supply sufficient heat for setting the cement but is at no time heated sufficiently to injure the support. The heating element is so made also that the support retains its flexibility so that it may readily conform to the shoe shape and sole yet resists deformation sufficiently to aid in shaping the sole to its original form and to prevent undue curling at the edges. Other features and details of the invention will appear from the specification and claims.

A preferred embodiment of the invention is illustrated in the accompanying drawing as follows:

Fig. 1 shows a central section through the apparatus on the line 1—1 in Fig. 2.

Fig. 2 a plan view of the pressure support, a portion of the pad being in section on the line 2—2 in Fig. 1.

Fig. 3 is a section on the line 3—3 in Fig. 2.

1 marks the base of the apparatus. A pressure support comprises the parts 2 and 3, and the parts 2 and 3 are connected by a hinge 4

so that these parts may more readily conform to the shapes of different shoes. The front of the plate 2 rests on a shoulder 5 on the base, and the rear supporting plate 3 has a projection 6 which rests in a socket 7 in the base. This arrangement of support permits the parts to adjust themselves for the proper curves.

The pressure support also includes the rubber supporting element 8 which is mounted on the supporting plates. This element is preferably of resilient rubber and in the preferred form the resilience of the rubber itself controls the cushioning effect of the support. The sole of the shoe 9 is placed on the support properly supplied with cement and the bottom of the shoe is placed on the sole. A pressure foot made up of the plates 10 and 11 connected by a hinge 12 is placed on the inside of the shoe in position to insert closing pressure to the support. A shank 13 extends from the plate 10. The shank 13 is provided with a screw socket 14 which is adapted to receive a thrust screw 15. The thrust screw 15 operates through a screw threaded arm 16 extending upwardly from the base.

It will readily be observed that with the shoe 25 in place, the bottom of the shoe and sole may be clamped together through the operation of the screw exerting pressure on the pressure foot. So far the structure is that in common use.

A heating element 17 is embodied in the rubber support. This is in zig-zag form made up of a series of loops having crosswise members 18, the crosswise members of each pair being connected by a longitudinal member 19. The adjacent members of successive pairs are connected by longitudinal members 21. The element is formed of flat wire and the turns of each of the loops are made by folding the wire upon itself as at 20 and 22. The laterally extending pairs which are connected at one side extend between the laterally extending pairs which are connected at the opposite side of the pad, so that the heat from the element is well distributed throughout the entire rubber support. In order to prevent the buckling or puckering of the rubber support at the point of greatest bend, namely adjacent the hinge 12, the loops at this point are brought in more remote from the edge of the pad.

Terminals 23 and 24 are provided for the ends of the element and these may be connected up to any convenient source of supply but ordinarily the element is subjected to a very low voltage such as 4 or 5 volts, but has sufficient current capacity to supply the necessary volume of heat.

Ordinarily the temperature of the element is brought to about 140° Fahrenheit.

It will be noted that the flat wire has a surface facing the surface of the pad contacting the sole. In other words, the flat wire is flatwise of the rubber support and is, therefore, very flexible so that the rubber support may be readily flexed both longitudinally and laterally with the rubber support to conform to the curves of the shoe bottom. The heat so introduced is arranged in close proximity to the sole, and so sufficient heat may be given to the contacting surfaces to rapidly set the cement, but the heat is not sufficient to injure the leather of the shoe or the rubber support. This heating of the rubber support reduces the setting time from one half to one third of what can be accomplished without the heat.

The flat wire not only readily yields to conform to the curve to which the rubber is subjected, but also supplies a greater heating surface so that there may be a more definite heat exchange between the wire and the rubber without excessive heat at the point of output.

25 What I claim as new is:—

1. In a shoe pressing machine, the combination of a sole support of resilient material of the nature of rubber, the thickness and resilience of the support alone controlling the cushioning effect of the support; a pressure foot adapted to exert pressure on a shoe bottom in contact with a sole on the support; and an electric heating element arranged in the support.

2. In a shoe pressing machine, the combination of a sole support of resilient material of the nature of rubber, the thickness and resilience of the support alone controlling the cushioning effect of the support; a pressure foot adapted to exert pressure on a shoe bottom in contact with a sole on the support; and a heating element of metal embedded in and in direct contact with the resilient material of the support.

3. In a shoe pressing machine, the combination of a sole support of resilient material of the nature of rubber, the resilience of the resilient material controlling the cushioning effect of the support; a pressure foot adapted to exert pressure on a shoe bottom in contact with a sole on the support; and an electric heating element formed of flat wire distributed through the sole support of resilient material with a face of the wire facing the sole contacting surface of the support.

4. In a shoe pressing machine, the combination of a sole support of resilient material of the nature of rubber, the resilience of the resilient material controlling the cushioning effect of the support; a pressure foot adapted to exert pressure on a shoe bottom in contact with a sole on the support; and an electric heating element of metal embedded in and in direct contact with the resilient material of the support, said metal

element being formed of flat wire having a face facing the sole contacting surface of the resilient support.

5. In a shoe pressing machine, the combination of a sole support comprising a yielding pad; a pressure foot adapted to exert pressure on a shoe bottom in contact with the support; and an electric heating element in the form of a flat wire distributed through the pad in zig zag loops, the face of the wire facing the sole supporting surface of the pad.

6. In a shoe pressing machine, the combination of a sole support of resilient material of the nature of rubber, the thickness and resilience of the resilient material alone controlling the cushioning effect of the support, said support comprising a backing formed of hinged sections; a pressure foot adapted to exert pressure on a shoe bottom in contact with a sole on the support; and an electric heating element arranged in the support.

7. In a shoe pressing machine, the combination of a sole support of resilient material of the nature of rubber, the resilience of the resilient material controlling the cushioning effect of the support, said support comprising a backing formed of hinged sections; a pressure foot adapted to exert pressure on a shoe bottom in contact with a sole on the support; and an electric heating element of metal embedded in and in direct contact with the rubber support, said metal element being formed of flat wire having a face facing the sole contacting surface of the resilient support.

8. In a shoe pressing machine, the combination of a sole support of resilient material of the nature of rubber, the resilience of the resilient material controlling the cushioning effect of the support; a pressure foot adapted to exert pressure on a shoe bottom in contact with a sole on the support; and an electric heating element comprising zig zag loops extending crosswise of the element and backing plates for the support formed of hinged sections, the loops of the element adjacent to the hinge being shortened.

9. In a shoe pressing machine, the combination of a sole support of resilient material of the nature of rubber, the resilience of the resilient material controlling the cushioning effect of the support; a pressure foot adapted to exert pressure on a shoe bottom in contact with a sole on the support; and an electric heating element of metal embedded in and in direct contact with the resilient material of the support, said metal element being formed of flat wire having a face facing the sole contacting surface of the resilient support and including resilient zig zag loops distributed through the support, said sides and ends of the loops being joined by folds of the wire.

MAXWELL C. SUERKEN.
